UNITED STATES PATENT OFFICE.

ARTHUR L. LEE, OF JAMAICA, NEW YORK.

LEDGER CARD SYSTEM, &c.

1.254.916.

Specification of Letters Patent. Patented Jan. 29, 1918.

Application filed May 1, 1917. Serial No. 165,684.

To all whom it may concern:

Be it known that I, ARTHUR L. LEE, a citizen of the United States, and a resident of Jamaica, county of Queens, and State of New York, have invented certain new and useful Improvements in Ledger-Card Systems, &c., of which the following is a specification.

While designed more particularly for the assembling and holding of ledger cards, the essential features of my invention are also applicable for use in connection with other similar card systems where convenience of access and use in a minimum of space is a desideratum.

Thus by my system a series of account or memorandum cards may be stored in a compact area in such manner that each is immediately accessible and available without disturbing the others in the system, and may be used *in situ* without actual removal from its prescribed location in the case, as hereinafter fully set forth,—the invention consisting in the specific construction and arrangement of parts described and claimed, and a distinctive feature being the mounting of the card holders in such manner that each is utilizable without detachment from the case, and without derangement of the other holders in the system.

In the accompanying drawings, Figure 1, is an isometrical perspective showing a case and card system embodying the essential features of my invention;

Fig. 2, is a side elevation of the case, partly broken away;

Fig. 3, is a cross section of the case on a larger scale;

Fig. 4, is a top view of one end of the case;

Fig. 5, is a cross section of a holder with cards supported on both sides thereof;

Fig. 6, an elevation of one end of a holder with an index card in place thereon;

Fig. 7, an isometrical view of the opposite side but same end of the portion of the holder shown in Fig. 6;

Fig. 8, a cross section of a holder without cards.

C, represents a cabinet, compartment, or casing of any desired or suitable construction, adapted to the purpose of accommodating and storing a series of card holders H, as hereinafter set forth,—the distinctive feature of the casing C, being its series of

coincidentally opposed upright grooves or runways c, which may be formed in any desired manner on opposite inner side walls of the casing.

In these side grooves rest trunnions h, 60 positioned on the holders H, at the lower corners thereof, and projecting beyond the end edges thereof. In the construction shown in the drawings these trunnions h, h, consist of extensions of a rod, bead, or equivalent h', extending the whole length of the holder H, and acting as a stiffening and reinforcing member thereto. The outer ends of the trunnions h, h, are preferably formed with bosses h², h², so as to snugly fit 70 the grooves c, c, and to contact with the groove-closure flanges c', c'; when the holders are raised to the fullest extent.

In order to economize space and render the system as compact as possible,—to avail 75 myself of the full capacity of the case C, as far as practicable,—I adapt each side of a holder H, to accommodate and support a ledger or similar index or record card L, although of course, obviously, only one side of 80 the holder H, may be thus employed if preferred. The cards L, are held in place on the holders H, by flanges h³, h³, which may be cheaply and conveniently formed by turning over the edges of the sheet metal 85 plate which constitutes the body plate of the holder, a sheet metal being best adapted for the purpose, although I do not confine myself to the use thereof since other material may be utilized in the formation of the 90 holders H, without departing from the spirit and intent of my invention in this respect.

The upper or outer edge of each holder H, is formed with a protuberant portion h⁴, 95 which answers the double function of a handle or finger lug, by which the holder H, may be conveniently raised from among its fellow holders in the case, and also of a number or index tab. Where both sides of 100 the holders H, are used for cards, and where numerals are used, as for instance to designate room numbers in a ledger card system for hotels as indicated in the drawings, one side of each tab h⁴, will bear the even number and the other side the odd number. Thus, in the drawings the even numbers face the front end of the case, while the odd numbers face toward the rear of the case; and the tabs h⁴, on adjacent holders are 110

stepped in position with relation to each other as illustrated in Figs. 1 and 3, so as to be readily observable and accessible.

Spring clips s , may be provided on the 5 holders to retain the cards in place thereon, and to also afford means for temporarily attaching an extra note ticket or memorandum slip when desirable. These clips s , may be soldered or otherwise secured rigidly 10 to the spine h' , or to the card retaining flanges h^3 , as may be found most expedient.

By way of illustrating the practical use and utility of my ledger card system we will suppose as before intimated that it is 15 used to keep the individual accounts of hotel guests. In such event when a guest registers, his name is placed on a card and is deposited in a holder corresponding in 20 number to that of the guest's room, the holder being raised *in situ* for the purpose and then dropped back into its position in the case. Subsequently whenever it is 25 desired to enter an item against the guest on the ledger card the holder bearing his room number is fully raised, (*i. e.*, as far as the retarding flange c' , will allow) and then turned over horizontally toward the front or rear of the case, according to whether 30 the number is odd or even, the necessary entry made while the holder is resting on the tops of the adjacent tabs h^4 , and the holder is then again raised perpendicular to the case and allowed to drop into its 35 normal position therein. The trunnions h , and bosses h^2 , sliding in the grooves c , permit of this action while preventing the disconnection and removal of the holder entirely from the case, thus also admitting of its selection and use without disturbing or 40 disarranging the other holders and cards in the case.

In Fig. 1, by way of illustrating the functions of the holders, two are shown as raised out of normal position,—one as raised perpendicular to the case and the other as raised and turned over horizontally for use. In practice of course only one holder and card is selected for use at one and the same time.

50 The holders H , may be formed with finger holes h^3 , h^5 , to facilitate the manipulation of the cards, especially their withdrawal when necessary from position on the holders.

The compactness of my card system, and 55 the quickness and convenience with which one and all the cards therein may be found, used, and returned to their normal positions, as well as the facility with which obsolete cards may be removed and new ones substituted in lieu thereof, renders it an important

factor in hotel management, as has been fully and successfully demonstrated; and its use and merits are no less applicable to other commercial and mercantile purposes.

What I claim as my invention and desire 65 to secure by Letters Patent is,

1. A card system of the character designated, comprising a case formed with a series of coincidentally opposed upright grooves and a series of holders adapted to receive and support a series of record reference cards, each holder being formed with bottom end trunnions fitting in said case grooves, so that each individual holder may be raised and used *in situ* without detachment from the case and without derangement of the other holders in the system, as set forth.

2. A card system of the character designated, comprising a casing formed with a series of coincidentally opposed upright grooves and a series of holders each adapted to receive and support two separate record reference cards, one on each side thereof, each holder being formed with bottom end 85 trunnions fitting in said case grooves, so that each individual holder may be raised and used *in situ* without detachment from the case and without derangement of the other holders in the system, as set forth. 90

3. A card system of the character designated, comprising a case formed with a series of coincidentally opposed upright grooves closed at top, and a series of holders adapted to receive and support a series of record reference cards, each holder being formed with bottom end trunnions fitting in said case grooves, so that each individual holder may be raised and used *in situ* without detachment from the case and without derangement of the other holders in the system, as set forth. 95

4. A card system of the character designated, comprising a case formed with a series of coincidentally opposed upright 105 grooves, and a series of holders adapted to receive and support a series of record reference cards, each holder being formed with spring clip retaining means and with bottom end trunnions fitting in said case 110 grooves, so that each individual holder may be raised and used *in situ* without detachment from the case and without derangement of the other holders in the system, as set forth.

ARTHUR L. LEE.
